UNITED STATES PATENT OFFICE.

FREDERICK J. WALLING, OF LOMAX, ILLINOIS.

HOT-WATER HEATER.

Application filed April 14, 1919. Serial No. 290,012.

To all whom it may concern:

Be it known that I, FREDERICK J. WALLING, a citizen of the United States, residing at Lomax, in the county of Henderson and 5 State of Illinois, have invented certain new and useful Improvements in Hot-Water Heaters; and I do hereby declare the following to be a full, clear, and exact description of the invention, such as will enable 10 others skilled in the art to which it appertains to make and use the same.

Particularly, my invention has for its object to provide a hot water heater or boiler of simple construction and exceedingly high 15 efficiency; and to such ends, generally stated, the invention consists of the novel construction and combination of parts hereinafter described and defined in the claims.

For convenience, this device will be hereinafter designated as a hot water heater, it being understood, of course, that this term includes a hot water boiler.

The present invention is directed chiefly to improved construction and relative arrangement of the sections of the heater whereby an exceedingly large amount of heat absorbing surface is exposed to the flames. In the drawings, the invention is illustrated as incorporated in an upright 25 cylinder of the water heater, but it will, of course be understood that certain of the features of the invention may be incorporated in heaters having various different cross sections arranged to operate either as upright or other hot water heaters.

Referring to the drawings, wherein like characters indicate like parts throughout the several views;

Fig. 1 is a rear elevation showing the preferred form of the heater, some parts being broken away and some parts being sectioned;

Fig. 2 is a view partly in side elevation but chiefly in vertical section on the line 45 2—2 of Fig. 1;

Fig. 3 is a plan view of one of the intermediate sections of the heater; and

Fig. 4 is a horizontal section taken approximately on the line 4—4 of Fig. 1.

The firepot section 5 of the heater is set 50 on a suitable base shell 6 that affords an ash pit, is provided with the customary ash door 7 and is equipped with a suitable grate 8.

The fire pot section 5 is formed with a 55 double wall to afford a surrounding water

chamber 9 into the lower portion of which opening is one or more cold water return pipes 10. At the lower portion of the front of the heater, the section 5 is shown as provided with a suitable clinker door opening 60 11 and cooperating door 12, and at its upper front portion, the said section 5 is formed with a fuel door opening 13 that is adapted to be closed by a fuel door 14 which, as will presently appear, is of such size that 65 it will also open and close a supplemental opening in the lower intermediate section, presently to be described.

In its top, the water chamber 9 of section 5, preferably at the back of the heater, 70 is provided with a large circulating port 15.

In building up this heater any desired number of intermediate sections 16 may be employed. These sections 16 are provided with water circulating ports 17, and the 75 port 17 of the lower intermediate section registers with the port 15 of the water chamber 9. Above the ports 17, the sections 16, in their top plates, are provided with similar water circulating ports 18. The port 80 18 of the lower intermediate section 16 registers with the port 17 of the section 16 that is placed on top thereof. The ports 17 and 18 of each intermediate section are separated by an oblique partition or web 19, (see 85 particularly Fig. 1, but also note the other views), that is cast integral with the section. Each intermediate section in this cylindrical form of heater, is formed with an annular outer or marginal main water channel 20 90 that is the full depth of the section, except at the front of the heater where the vertical depth thereof is reduced to afford openings 21. Here it may be noted that the opening 21 of the lower intermediate section 16 registers with the fuel door opening 13 of the fire pot section 5 and is arranged to be opened and closed by the fuel door 14 already noted. The openings 20 of the other intermediate sectional sections, each will be 100 closed by its own cleanout door 22.

Each intermediate section 16 is formed with a central water compartment 23 connected to the main water chamber 20 only by a neck portion. The said central water 105 chamber 23 is thus spaced from the surrounding annular main water chamber 20, so as to form a nearly annular or approximately C-shaped flame passage 24 with the water chamber 23 overlying the axial por- 110

tion of the heater. The water chamber 23 is divided by a vertical radial partition 25 that is formed as an inward extension of the oblique partition 19. By this arrangement, of partitions 19 and 25, the neck portion of the central water chamber 23, at one side of the partition 25 is connected to the annular main chamber 20 at a point below, and at the other side at a point above the 10 said oblique partition 19 (see particularly Figs. 1 and 4). By reference particularly to Fig. 1, it will be noted that the intermediate projected or central water chambers 23 of the intermediate sections in vertical 15 dimensions are much less than the vertical dimensions of the sections themselves, so that large flame passage or chambers 26 are formed between the inner portions of the said intermediate sections. It is also highly 20 important to note, for example, that the inwardly projected water chamber 23 of the intermediate section 16 that is second from the lowermost intermediate section, is of very considerable greater radial dimension 25 than the other lower section, so that the flame passages 24 of the adjacent intermediate sections, while concentric, or following the same general lines, are nevertheless, staggered or offset radially, so that the 30 flames, in passing upward, will be deflected radially inward and outward as indicated by arrows, Fig. 2, and will thus come into contact with all heat absorbing surfaces of the sections.

35 The top or drum section 27 of the heater is seated on the uppermost intermediate section 16, is made hollow to afford an annular or marginal water chamber 28 that is provided in its bottom plate with a port 29 that 40 registers with the port 18 in the uppermost intermediate section 16. The dome section 27 is formed with a central flue opening 30, which by a smoke pipe, not shown, will be connected to the chimney or stack. One or 45 more of the water lead pipes 31 is tapped into the top of the dome section 28. At the front of the heater, the dome section 27 is formed with a cleanout opening 32 adapted to be closed by a door 33.

50 Suitable gaskets or pockets will preferably be placed between the sections of the heater, and to detachably but rigidly unite the sections, the said sections are preferably provided with outstanding lugs 34 connected by nut-equipped bolts 35, as shown in Fig. 1.

55 As already indicated, the flames or hot gases, in passing up from the fire pot, are drawn through the nearly annular flame passages 24, are deflected against the inner surfaces of the marginal water chambers 20 and are caused to completely envelop the inwardly projecting water chambers 23. Moreover, as they pass upward, the flames or gases 60 are caused to take a sort of zigzag radially inward and outward course in going from the

one passage 24 to the other, which is out of line therewith.

When the hot gases reach the dome or top section 27, they strike the top and side walls of the interior surfaces thereof, so 70 that by the time these gases reach the outlet 30, the greater part of the heat thereof will have been absorbed and conducted into the water of the heater. Preferably, the outlet or flue connection 30 has a conducting capacity slightly less than the heat of the approximately annular flame passages 24, so 75 that there will be a slight choking or retarding at the very point where the hot gases leave the heater, but have very free circulation 80 between the sections themselves. This prevents waste of heat and gives the hot gases the complete inflow and will cause them to come into good contact with all of the inner exposed heat absorbing surfaces 85 of the heater.

The water, on its upward passage through the heater moves upward, first from the water jacket of the fire pot where it has already been heated to a very considerable extent, and thence, to the first section 16. Upon entering through the port 15 it is divided into two streams, the main portion being caused to pass completely around the marginal chamber 20 (see arrows marked *a*, 90 Fig. 4), and a lesser portion being caused to take a circular course through the inner chamber 23, as indicated by arrows marked *b* on Fig. 4. These two streams reunite at the upper side of the oblique partition 19 95 and from thence, pass through the top port 18 of the first intermediate section through the port 17 of the second intermediate section and are caused to take a similar divided course through the second intermediate 100 section, and so on, until the hot water finally reaches the dome section 27 through its port 29, and from thence, is drawn to and radiates through the hot water pipes 31. The water is thus kept in contact with hot 105 walls for a comparatively long time and is caused to make a long tortuous course through the heater and is exposed to a very large amount of the hot heating surface.

No only is the heater above described 110 very highly efficient, but is of comparatively simple construction and reasonably small cost and may be very easily kept clean so that its radiating surface will always have a maximum heating efficiency. 115 Preferably, the sections, and in fact, the entire heater, is made of cast iron.

What I claim is:

1. A heater of the class described comprising superposed sections in contact at 120 their outer portions which are formed as annular water chambers, each section having a central water chamber spaced from said annular chamber except at a connecting neck portion thus forming a nearly 125

annular flame passage, said outer water chambers having connecting ports alined with said neck portions, inclined partitions in said outer chambers adjacent said ports and having extensions projecting into said neck portions and central chambers and forming passages whereby part of the water is caused to circulate around said annular chambers and part to circulate through said central chambers around the partition extension therein.

2. The structure set forth in claim 1, the central chambers of successive sections being of different extent whereby the smoke passages are vertically staggered.

3. The structure set forth in claim 1, the central chamber being of less height than the outer annular chambers, whereby flame passages are formed in which the flames contact the inner side of the outer annular chambers beneath said central chambers.

4. The structure set forth in claim 3, the outer annular chambers being of less height

in the front portion of said heater to form clean out passages for the last mentioned frame passages and clean-out doors arranged at the front of said clean-out passages.

5. A heater of the class described comprising superposed sections in contact at their outer portions and formed as annular water chambers, each section having a central water chamber spaced from the sectional annular chamber except that a narrow connecting neck portion thus forming nearly annular flame passages, said annular chambers being of less height at the front of the furnace than at the other portions to form cleanout passages.

In testimony whereof I affix my signature in presence of two witnesses.

FREDERICK J. WALLING.
